UNITED STATES PATENT OFFICE.

SAMUEL D. MOTT, OF PASSAIC, NEW JERSEY, ASSIGNOR OF ONE-HALF TO ARTHUR B. SULLIVAN, OF ALLENDALE, NEW JERSEY.

SOUND REPRODUCING AND RECORDING APPARATUS.

1,299,853.

Specification of Letters Patent.

Patented Apr. 8, 1919.

Application filed February 7, 1916. Serial No. 76,641.

To all whom it may concern:

Be it known that I, SAMUEL D. MOTT, a citizen of the United States, and a resident of Passaic, in the county of Passaic and State of New Jersey, have invented certain new and useful Improvements in Sound Reproducing and Recording Apparatus, of which the following is a specification.

This invention relates primarily to sound reproducing apparatus of that class wherein the recorded sound is impressed in a spiral groove on the face of a flat disk and herein termed a "disk record."

The broad object of the invention is the extension of the field of the sound reproducing machine industry by broadening the scope of the apparatus and thereby increasing its utility. This broad object is attended by numerous more specific objects such as increasing the range or time of action of the apparatus by enlarging the range of sound reproduction which can be reproduced as a continuous record either to a limited extent or unlimited by continuous repetition.

Another object is to maintain the individuality of the various instruments or sounds which are reproduced as a single concerted composition and thereby increase the accuracy and tonal harmony of the reproduced sound.

As is well known in this art the utility of the ordinary "phonograph" of the disk type is limited owing to the fact that to properly reproduce the recorded sound it is necessary to maintain some semblance to tangency of the stylus to the groove in which it is travelling and as the most practical manner of operation is by means of a rotating record and a swinging reproducer arm, the size of the record is limited owing to the stylus canting too much off the tangent when the record is beyond certain limits. For this reason the size of the compositions which could be reproduced was limited. According to this invention whole operas may be reproduced as a continuous record as well as other lengthy compositions such as lectures, &c.

Also in accordance with one of the forms of the invention the reproduced composition may be repeated indefinitely without any manual operation being necessary. In other words, a continuously operative orchestra, band or concert instrument is attained for use in moving picture theaters, auditoriums, lobbies, dancing halls and public places gen-

erally. Given motion, the reproducing instrument will run indefinitely or until worn out.

The invention also attains, in one of its forms, an entirely new result in the phonographic reproduction of sound; to wit, the maintaining of the individuality of each instrument or voice brought together in concert. All doubtless agree that the more familiar we are with the phonographic principle the more amazing it is that a needle and a matrix will record and repeat the multitude of even the major vibrations of an orchestra, very imperfectly to be sure but sometimes recognizable as such. The reproduction is imperfect because the individuality of the instruments is lost and we get vibrant tone effects with incidental harmony. The rationale of orchestra or band is variety and volume and this is not obtained unless identity is preserved. It is evident if a perfect piano record and a perfect violin record were sounded synchronously as originally rendered, a perfect mechanical orchestra with the individual characteristics of each instrument preserved would be attained. Otherwise all of an instrumental group may as well play a violin, for instance, because all tones of given pitch have the same number of vibrations per second. A violin pitch of A is recognized from a piano pitch of A by the microscopic quivers in the major vibrations called half-tones, partials and over-tones which distinguish and identify each instrument. From the very nature of the materials used these half-tones, partials and over-tones, so important in orchestral and concert harmony and even some of the major vibrations lose their identity, tone, characteristics or timbre. According to this invention, in one of its forms, the loss or mutilation of these vibrations so they cannot be recognized is prevented by providing all instruments with their own records sounding in concert. In the drawings in this application illustrating this part of the invention, four records are shown for each instrument and the same is shown as arranged for four instruments but the number of instruments may be increased to a full orchestra and more or less records for each instrument may be provided. In other words the apparatus may be constructed for any number of instruments or voices and any length of full-toned music. Each in-

strument is provided with its own individual sound-box and stylus transmitting the sounds to a common exit or horn and the sound from any or all instruments or voices 5 may be stopped by lifting its sound-box from the record. If a quartet is reproduced, the soprano may sound, then the alto or the tenor or the bass or all together or in any combination, for entertainment or teaching vocalization. It may be utilized for 10 teaching languages by individually reproducing sentences, phrases, idioms of the English, French, German and Spanish tongues for comparison and familiarizing.

15 The invention consists in the improved apparatus for reproducing sound hereinafter more particularly described and then specified in the claims.

In the accompanying drawings, the invention is illustrated in a more or less diagrammatic manner as very little structural change 20 is necessary in the phonograph *per se* and the necessary details of construction will be readily understood by those skilled in this 25 art.

Figure 1 is a plan view of a sound reproducing apparatus in accordance with this invention in one of its forms to wit, that in which a plurality of disk records provided 30 with sound grooves arranged as a continuation one of the other and provided with a common sound box and stylus. In this form the composition cannot be repeated except by bringing the stylus back to its initial position manually.

Fig. 2 is an enlarged edge elevation of the record disks shown in Fig. 1.

Fig. 3 is a plan view of the record disks separated from each other and looking at 40 the bottom of the records, the disks being turned upside down.

Fig. 4 illustrates, in plan view, a slight modification in the disks.

Fig. 5 is an enlarged cross-section and 45 partial side elevation taken on the line 5—5 Fig. 4.

Fig. 6 is a plan view of a sound reproducing apparatus in accordance with this invention in another of its forms, to wit, one in 50 which a very lengthy production may be reproduced and repeated automatically any number of times.

Fig. 7 is an edge view of the turntables supporting the disks shown in Fig. 6 and 55 illustrates the canted overlapped arrangement on an exaggerated scale.

Fig. 8 is a diagrammatic view illustrating a driving means which might be employed for rotating the turntables used in the form 60 shown in Fig. 6.

Fig. 9 is a plan view of an arrangement in accordance with this invention in which the records are arranged in group succession, that is, each group has recorded sounds 65 from a single source and each group is pro-

vided with a sound-box and stylus all of which transmit the recorded sounds to a common exit.

Fig. 10 is a view similar to Fig. 9 showing but part of the circular arrangement, 70 the record disks and reproducer arms being removed.

Fig. 11 is a plan view of a recording apparatus suitable to produce records for use in the reproducing apparatus shown in Fig. 75 9.

Fig. 12 is a plan view of the same with the megaphones and turntables removed.

Fig. 13 is a transverse cross-section taken on the line 13—13 Fig. 12, parts being shown 80 in elevation.

Fig. 14 illustrates a guiding device which might be employed in connection with the stylus to properly direct the stylus to its proper groove in a succeeding record.

Fig. 15 illustrates the same in passing 85 from one record to another.

Fig. 16 is a side elevation of the parts shown in Figs. 14 and 15.

This invention in all its forms contemplates by preference the employment of flat disk records of the usual type in that they are provided with sound grooves spirally arranged and by the rotation of the record the stylus is caused to travel in the record 95 groove and across the face of the record. The stylus, sound-box and reproducer arm may be of any desired suitable construction; in the forms shown it is typified as the usual stylus which acts on the diaphragm of the 100 sound-box carried by the usual hollow swinging reproducer arm which transmits the sound to a megaphone or other exit.

The sound-box is pivotally mounted on the end of the reproducer arm so as to engage 105 the face of the record disks by gravity as is usual. In the record disk as employed in the ordinary single disk machine the record groove starts near the outer edge and terminates at the center whereas in a record disk 110 for use in this invention the record groove starts at the center and runs off into space at the outer periphery so that the stylus travels off the periphery of one record and into the record groove of the next record. 115

Referring particularly to the form shown in Figs. 1, 2 and 3, three record disks are shown although more or less number may be employed. The record disks 1, 2 and 3 are mounted above a suitable support such 120 as a cabinet 4. The record disks are each provided on their upper surface with a spiral record groove, the sound waves of which being by preference located on the side walls although they might be located in 125 the bottom if desired. In the drawings the record grooves in these as well as the balance of the figures are shown exaggerated for simplicity and clearness. The peripheries of the disks 1, 2 and 3 are preferably each 130

provided with a groove 5 of any desired character. The periphery of each record disk or at least all disks except the last of the series which is indicated at 1 in the drawings is preferably eccentric and provided with a notch or shoulder 6 where the record groove leaves the record disk. In the arrangement of the invention shown in these figures the record disks are partially superposed on each other in horizontal planes and in such position that the notch or shoulder 6 is directly above or the record groove terminating at the shoulder is directly in line with the inner record groove of the next succeeding disk so that the grooves make a practical continuation one of the other.

10 The disk 1 is mounted on and carried by a standard or post 7 rising from the cabinet 4 and to which rotation is given by any suitable form of motor (not shown) and which may be conveniently located in the cabinet. The disk 1 is connected to the standard 7 by a central pin 8, preferably square to position the record, the disk being provided with a corresponding opening 9. 10 indicates a vertical idler spindle suitably mounted on or in the cabinet 4 and provided with pinions or wheels 11 and 12 fast thereon and one above the other in such position that they engage in the grooves 5 of the disks 1 and 2. 13 indicates a similar spindle provided with pinions or wheels 14 and 15 engaging in the grooves 5 of disks 2 and 3. Similar spindles and superposed wheels engage in the grooves 5 at the rear edge of the disks, the upper pinion or wheel of each being indicated at 16 and 17. 18 indicates a spindle provided with a wheel 19 which engages in the groove 5 of the disk 3 at the outer edge.

Rotation given to the spindle 7 is communicated to the disk 1 by pin 8 and in turn transmitted to the disks 2 and 3 by the pinions or wheels working in the grooves 5. 45 The pinions or wheels serve to support as well as drive the disks 2 and 3 as well as similar pinions would support and drive any additional number of disks which might be added to the series. Thus the disk 1 is driven by the spindle 7, the disk 2 is driven by the wheels 12 and 16 receiving power from the wheel 11 and the wheel on the spindle beneath wheel 16 respectively and the disk 3 is driven from the disk 2 by the wheels 15 and 17 receiving power from the wheel 14 and the wheel beneath the wheel 17 respectively. The disk 1 is supported by the spindle 7, the disk 2 is supported at three points by the wheels 12, 14 and 16 and the disk 3 is supported at three points by the wheels 15, 17 and 19.

To position the records in this form of the invention in proper correlation so that the reproduced sound of the records will successively synchronize, I preferably pro-

vide the lower flange at the periphery of the records formed by the groove 5 with cut-away places 20 (see Fig. 3) in such positions that the record disks can only be placed in position over the supporting and driving 70 spindles through these cut-away parts and when so placed the record grooves of each record will form a continuation of the prior one.

15 The record disks 1, 2 and 3 are arranged with their centers in the arc of a circle in the center of which circle a hollow reproducer arm 21 is pivotally mounted to swing freely. The reproducer arm carries at its outer end the usual gravity sound-box 22 80 provided with a stylus adapted to travel in the record grooves of the disks.

20 The operation is considered to be obvious—rotation given the record disks as previously described, the stylus and sound-box 22 85 travels across the face of each record and successively from one to the other. When the stylus reaches the notch or shoulder 6 of any record it drops off that record and down onto the next succeeding record and 90 so on. If desired, guiding means for the stylus to the proper groove in the succeeding record as shown in Figs. 14, 15 and 16 and subsequently herein described may be employed.

25 The reproducer arm 21 conducts the reproduced sounds from the sound-box to a horn or megaphone of any desired character preferably but not necessarily located in the cabinet 4. This part of sound reproducing 100 apparatus is now so well understood and the present invention not being limited in any of its forms to any particular manner of delivering the reproduced sound from the reproducer arm, any detailed description of 105 this part of the apparatus is deemed unnecessary herein.

If desired in this and in the succeeding forms of the invention the record groove at the place of transference of the stylus from one to another may be so arranged that no sounds are reproduced at that point, that is it may come at a natural pause in the reproduction. Also it will be understood that instead of the record disks 2 and 3 being frictionally driven the driving and supporting wheels may be toothed pinions engaging teeth formed in the periphery of the disks as will be described in connection with the driving of the turntables in some of the 115 forms subsequently described herein.

30 The record disks instead of having record grooves terminating at a notch or shoulder as in the previous form might merely shoot directly off the edge of the disks at a tangent to the grooves as indicated at 23 in Fig. 4. In this figure the disks 1 and 2 are shown and instead of the positioning means of the previously described form, a positioning finger 24 may be employed. This finger 130

is pivotally mounted on a stud 25 and engages a notch in the periphery of the disk and after the disk is positioned and before starting the mechanism the finger 5 is withdrawn. In this form of the invention the disk 2 is slid edgewise against the driving pinions 12 and 16 and an additional supporting pinion 26 is then brought up into operative position. Instead of engaging the 10 disks in a groove as in the previous form the pinions are shown as provided with flanges which engage opposite surfaces of the disk as indicated in connection with the pinion 26 in Fig. 5. The pinion 26 as shown more 15 clearly in Fig. 5 is mounted on and carried by a sliding standard 27 reciprocated by an adjusting nut 28 to bring the pinion into and out of engagement with the periphery of the disk 2. By means of this adjustable 20 mounting of pinion 26 the traction of the pinions 12 and 16 may be adjusted.

Referring to Figs. 6 to 11 inclusive, an arrangement is shown whereby the sounds recorded on the disks may be repeated *ad infinitum* without any manual operation being necessary to re-set. The manner of mounting and operating the records employed in the forms of the invention illustrated in these figures is the same, the reproducing 25 action and the control of the reproduced sound being different however in Fig. 9 than in Fig. 6. The action and principle illustrated in Fig. 9 will be presently described.

29 indicates a plurality or series of record disks partially superposed one above the other and each provided with a spiral record groove starting at the center of the disk and running off the periphery at the notch or shoulder 6 as described in connection with the disks 2 and 3 of the form shown in Fig. 1. The disks 29 are annularly arranged in a complete circle and each disk is provided with a supporting turntable 30. The turntables 30 are arranged parallel with each other but are slanted from the horizontal as indicated in Fig. 7 whereby the stylus traveling in the grooves of the disks 29 carried by the turntables ascends in going from the center to the edge and then drops to the center of the next succeeding record and so on. By this slant arrangement of the turntables and records the stylus can travel continuously around the circle of records an indefinite number of times until stopped or the parts become worn or the driving power gives out. If desired a corresponding slant may be given the sound-box carrying the stylus so the stylus will enter the groove in a vertical plane. The degree of slant to be 55 given the turntables and records depends on the thickness and diameters, the slant being shown exaggerated in the drawing for clearness.

31 indicates a plurality of spindles or 60 shafts suitably mounted on a support 32 and

disposed perpendicular to the plane of the turntables 30. The shafts 31 are annularly disposed about the center of the turntable arrangement and one at each place of intersection of the turntables as clearly shown in Fig. 10. Each shaft has two driving pinions 33 and 34 fast thereon. To prevent slippage said pinions are preferably toothed wheels and each engages a toothed rack formed in a groove 35 in the edge of the turntables 30. At the lower end of each shaft is a pulley 36 by which rotation is given to the shafts in any desired manner, a convenient construction being shown in Fig. 8 in which an endless belt 37 receiving power from a motor 80 shaft 38 and pulley 39 travels around in engagement with all the pulleys on the shafts 31.

70 The pinions 33 and 34 thus both drive the turntables and support the same at one point. If desired power need be applied to but one shaft 31 in which case the rotation of the turntables will be effected by each transmitting its motion to the next by means of the pinions.

75 The turntables are supported at the outer circle of the arrangement by pinions 40 similarly arranged to the pinions 33 and 34 and also working in the toothed groove 35 of the turntables.

90 Each turntable is provided with a centering pin 41 and a positioning pin 42 both of which enter holes in the bottom of the record disks 29. The positioning hole in the disk is so placed that when the disks are properly placed on the turntables the record groove of a disk where it leaves the disk at the shoulder 6 will lead directly to the beginning of the record in the groove in the next succeeding disk thus insuring proper continuity 100 of the intended correlation between the records at all times.

105 In the form shown in Fig. 6 a single reproducer arm 43 is provided for all records. The arm is freely mounted to swing about the center of the arrangement and is provided with the usual gravity sound-box 44 carrying a stylus needle adapted to travel across the face of the record disks 29 in the grooves thereof and successively from one 110 record to another. By this arrangement the rotation given the records 29 by means of the driving pinions 33 and 34 acting on the turntables 30 causes the stylus to travel in the well known manner. When the stylus reaches the end of the groove at the periphery of one record it drops down into the first groove in the next succeeding record and so on around the complete circle, traveling through the record grooves of each disk successively and then repeating the cycle any 115 number of times desired.

120 In the arrangement shown in Fig. 9 the individual records 29 in certain groups are each assumed to have recorded thereon the 125

sounds from but one instrument, to wit one group has notes from a cornet, another a piano, another a clarinet and another a violin, four record disks being provided to 5 each group. A reproducing device having one reproducer arm for each individual instrument or group of records is provided. The reproducer arms indicated at 45, 46, 47 and 48 are each provided with a gravity 10 sound-box and stylus and are mounted to swing about a common center 49 formed as a common horn or exit to which the sounds from all the horns are transmitted.

By this arrangement the individual notes 15 of each instrument are individually reproduced and brought together at the exit thus maintaining the individuality of each instrument embodied in the orchestra. The reproducer arms travel continuously around 20 carrying the sound-boxes and styli successively from one record to another, one sound-box and stylus engaging a record of each instrument at all times. More or less instruments may be represented, in which 25 case one horn and sound-box is provided for each instrument. If desired to omit any instrument or instruments from the concerted effect, one or more of the sound-boxes may be turned back out of contact with the 30 face of the records. It will be understood that other sounds than those indicated may be reproduced in accordance with the principle illustrated in this form.

If found desirable to positively guide the 35 stylus to the next succeeding record and prevent a sudden drop, a guiding device shown in Figs. 14, 15 and 16 may be employed. With reference to these figures, 50 indicates the stylus carried by the sound-box. 51 indicates a block of any suitable material 40 through which the stylus passes and to which it is secured in adjusted position by screw 52. 53 indicates a V-shaped pointed guide secured to the block 51. The point of 45 the guide is at some distance above the end of the stylus and in line with the axis thereof when viewed from the front. As the stylus slips off the edge of the record the side edge of the guide engages the edge of 50 the record as shown in Fig. 15 and the stylus drops down onto the next record, it being guided to its proper groove by the side of the guide sliding down the edge of the record. This also serves to break any sudden 55 drop of the stylus. The point at which the stylus engages the succeeding record may be adjusted by varying the position of the guide on the stylus by means of the screw 52.

A recording apparatus suitable for making 60 records to be used in the forms of this invention shown in Figs. 6 and 9 is illustrated in Figs. 11, 12 and 13. Receivers of sound such as megaphones 60 may be arranged on a platform above the apparatus 65 or may be located in separate rooms or in-

closures. In the arrangement shown four megaphones are used although it will be understood any desired number may be provided. The megaphones are connected to sound-boxes 61 either directly, as shown in 70 two instances or by means of flexible pipes 62 as shown in the other two instances. The sound-boxes are provided with the usual recording stylus and are pivotally mounted on the ends of arms 63 mounted stationary on 75 a stationary vertical standard 64. The standard is fixedly mounted in a base 80.

65 indicates a series of partially superposed turntables similar in construction and arrangement to those used in the reproducing apparatus described in connection with Figs. 6, 7, 9 and 10. The turntables 65 are mounted upon and carried by a common turntable 66 by means of pairs of pinions 67 carried by spindles 68 rising from arms 69 80 projecting outwardly from the turntable 66 and pairs of pinions 70 carried by spindles 71 rising from the turntable 66, near the inner edge. If desired the pinions 70 may also be provided with teeth as in the case of 90 the pinions 67.

Each turntable 65 is provided with centering and positioning pins corresponding to those used on the turntables 30 of the reproducing apparatus.

The turntable 66 is rotated bodily counterclockwise as indicated by arrows by means of an electric or other motor 73, mounted on the turntable. A shaft 74 driven by the motor and mounted in bearing 75 on the 100 turntable 66 is provided with a worm gear 76 which meshes with a pinion 77 secured to the fixed post or standard 64. Rotation of the shaft 74 rotates the common turntable 66 by the worm 76 traveling around the 105 standard 64.

Worm gears 78 on the shaft 74 engage and 110 rotate pinions 79 which in turn rotate the turntables 65, the rotation being transmitted to all the turntables by the pinions 70 and 67.

In this manner the turntables 65 are rotated individually on the turntable 66 and carried around bodily by the rotation of the common turntable 66. When the record disks are placed on the turntables 65 and 115 the recording styli placed in operative position the sounds delivered to the megaphones 60 will be recorded on the disks in the well known manner, the styli successively engaging one disk after another as 120 the records are rotatively fed beneath them. When the common turntable has been rotated so far that a previous recorded disk reaches the next stylus the recording mechanism is stopped. The rotation of the 125 common turntable 66 is naturally very much slower than that given the turntable 65, the proper speed being determined by the pitch of the worms 76 and 78.

The reproducing device is an exact di- 130

dimensional duplicate of the recording device so that the synchronism of the records when placed on the reproducing machine is exact.

It will be understood that the invention is not limited to the constructions as shown and described, the same being for the purpose of illustration only.

Also it will be understood that I do not limit myself to the construction or operation of recording apparatus as shown and described for making the records to be used in the reproducing apparatus.

What I claim as my invention is:—

1. In an apparatus for reproducing sound, the combination of a plurality of disk records each having record grooves starting at the center and terminating at the outer edge, means for rotating said records and a stylus traveling in said grooves from the center 15 to the outer edge of the record and dropping off the outer edge by gravity onto the next record.
2. In an apparatus for reproducing sound, the combination of a plurality or series of disk records having record grooves starting at the center, means for driving said records simultaneously and continuously and a stylus traveling in said grooves and dropping off the edge of one disk onto the next by 25 gravity.
3. In an apparatus for reproducing sound, the combination of a plurality or series of disk records driven simultaneously in fixed relation to each other and each disk provided with a record groove starting at the center and running off the outer edge and a stylus traveling in said groove and dropping from the edge of one disk to the next 35 succeeding one by gravity.
4. In an apparatus for reproducing sound, a series of partially superposed disk records, the grooves of each record starting at the center of the disk and terminating at the outer edge and a stylus traveling in said 40 grooves and running off the outer edge of each record disk and onto the next succeeding record disk at the center.
5. In an apparatus for reproducing sound, a series of partially superposed disk records, the grooves thereof starting at the center of each record and terminating at the outer edge, said disks rotating in fixed relation to each other and a stylus adapted to travel in said grooves, said stylus running 50 off said edge and engaging the center of the next succeeding disk.
6. In an apparatus for reproducing sound, a series of disk records arranged in an arc, the grooves of each record starting at the center and terminating at the outer edge and a stylus passing over said records in the grooves thereof, said stylus dropping by 55 gravity from the edge of one disk onto the next succeeding disk.
7. In an apparatus for reproducing sound,

the combination of a series of partially superposed disk records annularly arranged in a complete circle, each disk being provided with a record groove starting at the center and running off the outer edge and 70 an annularly swinging stylus adapted to travel in the grooves of said records and drop by gravity from the edge of one disk onto the next succeeding disk.

8. In an apparatus for reproducing sound, 75 a series of disk records partially superposed on each other and arranged in a complete circle, the grooves in said records starting at the centers thereof and terminating at the outer edge and a stylus traveling in said 80 grooves and passing successively and continuously from one record to another.

9. In an apparatus for reproducing sound, 85 a series of partially superposed disk records annularly arranged in a complete circle and each provided with a record groove starting at the center of the record and going off into space at the outer edge, a swinging reproducer arm swinging from the center of the circle formed by the records and a stylus carried by said arm and passing successively and continuously over said records from one to the other.

10. In an apparatus for reproducing sound, 95 a series of partially superposed disk records each provided with a groove starting at the center and terminating at the outer edge, driving means for rotating said records simultaneously and a stylus passing successively over said records from the center to the outer edge of each record and thence by gravity to the center of the next record.

11. In an apparatus for reproducing sound, 105 a series of disk records having sound grooves thereon and each record partially overlapping the next succeeding record, a series of turntables each supporting one of said records, driving means engaging the peripheries of said turntables and a stylus 110 traveling across the records in the grooves thereof and successively passing from one record to another.

12. In an apparatus for reproducing sound, 115 a series of partially superposed disk records, a series of turntables each supporting one of said records, driving means for rotating said turntables and engaging the peripheries thereof, said driving means supporting said turntables and a stylus passing 120 successively over said records in the grooves thereof.

13. In an apparatus for reproducing sound, 125 a series of partially superposed disk records, a series of turntables each supporting one of said records, means for rotating said turntables, said means also supporting said turntables and a stylus adapted to travel over the face of said records successively.

14. In an apparatus for reproducing sound, a series of partially superposed disk records, a turntable for each record, means adapted to both rotate and support said turntables and a stylus passing over said records successively from one to another.
15. In an apparatus for reproducing sound, a series of partially superposed disk records, turntables upon which said records are supported, driving pinions adapted to support said turntables and engaging the peripheries thereof and a stylus passing over said records successively from one to another.
16. In an apparatus for reproducing sound, a series of partially superposed disk records, a turntable upon which each record is supported, driving pinions engaging the peripheries of said turntables for rotating the same in synchronism and a stylus passing over said records successively from one record to another, said driving pinions also supporting said turntables and the record disks carried thereby.
17. In a sound reproducing apparatus, a series of disk records partially superposed on each other and annularly arranged to form a complete circle, the grooves of each record starting at the center and terminating at the outer edge and a stylus passing over said records and successively from one record to another by gravity whereby said stylus may continuously travel from one record to another and reproduce the resultant sound without interruption for an unlimited number of complete cycles.
18. In a sound reproducing apparatus, a series of disk records arranged consecutively in a complete circle and a stylus adapted to pass over said records and by gravity from one record to another, said records being arranged overlapping each other and slanting from the horizontal whereby said stylus may travel continuously around the circle of records an indefinite number of times.
19. In a sound reproducing apparatus, a series of disk records arranged parallel with each other and at an angle to the horizontal and partially superposed one above the other, said records being arranged in a complete circle, a reproducer arm mounted to swing from the center of said circle of records and a stylus carried by said arm passing over said records and successively from one record to another whereby said stylus may travel continuously for any number of complete cycles of the series of records.
20. In a sound reproducing apparatus, a plurality of sound reproducing disk records arranged in group succession and a plurality of styli one for each group of records adapted to pass over said records successively and continuously from one record to the next succeeding record.
21. In a sound reproducing apparatus, a plurality of sound reproducing disk records arranged in group succession, the grooves in each record starting at the center and terminating at the outer edge and an independent stylus for each group, said stylus traveling in the record grooves from the center to the outer edge and then dropping off the outer edge by gravity onto the next record.
22. In a sound reproducing apparatus, a plurality of sound reproducing disk records arranged in group succession, the grooves in each record starting at the center and terminating at the outer edge and an independent stylus for each group passing successively over the records of said group and then continuing without interruption on to the next group, the stylus traveling in the grooves from the center to the outer edge and then by gravity onto the next succeeding record at the center.
23. In a sound reproducing apparatus, a plurality of sound reproducing disk records arranged in group succession and a stylus for each group of records, all of said styli being adapted to travel by gravity from one record to the next succeeding record of the group and transmitting sound to a common megaphone or horn.
24. In a sound reproducing apparatus, a plurality of partially superposed disk records annularly arranged in group succession, a stylus for each group of said records adapted to travel successively and continuously over said records and by gravity from one record to another and a common megaphone or horn into which each stylus independently delivers its reproduced sound.
25. In a sound reproducing apparatus, a plurality of partially superposed disk records provided with spiral sound grooves starting at the center of each record and running off the edge, a stylus traveling across said records in the grooves thereof and successively and continuously from one record to another and means for guiding said stylus from one record to its proper groove in the next succeeding record.
26. In a sound reproducing apparatus, a plurality of partially superposed disk records provided with spiral sound grooves starting at the center of each record and running off the edge, a stylus traveling across said records in the grooves thereof and successively from one record to another and a guide on said stylus adapted to lead said stylus from one record to its proper groove in the next succeeding record.
27. In a sound reproducing apparatus, a plurality of partially superposed disk records provided with spiral sound grooves starting at the center of each record and running off the edge, a stylus traveling across said records in the grooves thereof and successively from one record to another.

and an adjustable guide secured at the side of said stylus for guiding said stylus from one record to another.

28. In a sound reproducing apparatus, a series of partially superposed disk records having spiral grooves starting at the center of each record and running off the edge, said records being provided with a shoulder in the periphery at which shoulder the groove terminates, a stylus passing over the said records in the grooves thereof and successively from one record to another and a guide engaging the periphery of a record disk after said stylus leaves said shoulder and adapted to lead said stylus properly to the groove in the next record.

29. In a sound reproducing apparatus, a plurality of partially superposed continuously rotating disk records each forming a continuation of the preceding one, each record being provided with a groove starting at the center and terminating at the outer edge, means for rotating said record disks, a common stylus for said records traveling by gravity from one record to the other, and means for positioning said records to secure and maintain proper correlation.

30. In a sound reproducing apparatus, a plurality of partially superposed continuously rotating disk records each forming a continuation of the preceding one, each record being provided with a groove starting at the center and terminating at the

outer edge, means for rotating said record disks, a stylus passing consecutively over said records and by gravity from one record to the next, and positioning means for securing and maintaining proper correlation or synchronism between said records.

31. In a sound reproducing apparatus, a plurality of partially superposed continuously rotating disk records each forming a continuation of the preceding one, each record being provided with a groove starting at the center and terminating at the outer edge, a turntable for each record disk and means associated with said disks and turntables for positioning said disks thereon to secure proper correlation between said record disks.

32. In a sound reproducing apparatus, a plurality of partially superposed continuously rotating disk records each forming a continuation of the preceding one, each record being provided with a groove starting at the center and terminating at the outer edge, a turntable for each record disk, a centering pin and a positioning pin on said turntables adapted to engage and position the record disks thereon.

Signed at New York, in the county of New York and State of New York, this 1st day of February A. D. 1916.

SAMUEL D. MOTT.
